UNITED STATES PATENT OFFICE.

FRANK C. MOCK, OF CHICAGO, ILLINOIS, ASSIGNOR TO STROMBERG MOTOR DEVICES COMPANY, OF CHICAGO, ILLINOIS, A CORPORATION OF ILLINOIS.

CARBURETER.

1,339,214.

Specification of Letters Patent.

Patented May 4, 1920.

Application filed March 22, 1917. Serial No. 156,603.

To all whom it may concern:

Be it known that I, FRANK C. MOCK, a citizen of the United States, residing at Chicago, in the county of Cook and State 5 of Illinois, have invented a certain new and useful Improvement in Carbureters, of which the following is a full, clear, concise, and exact description, reference being had to the accompanying drawings, forming 10 a part of this specification.

My invention relates to carbureters for internal combustion engines and is concerned particularly with improved means for securing a proper combustible mixture 15 upon idling or low speed operation. A frequent difficulty with an ordinary carbureter is the deposit of liquid fuel upon the walls of the air passageways and the carbureting chamber, this being due to the 20 fact that upon low speed and idling the suction below the usual throttle is very low, sufficient however to draw the gasolene from the nozzle but insufficient to carry the gasolene on to the engine in vaporized state. 25 It has been proposed heretofore to feed the low speed or idling mixture above, that is on the engine side of, the throttle.

My invention proceeds from that fundamental idea and contemplates an improved 30 and simplified structure, together with improved means of control.

My invention will be clearly understood by reference to the accompanying drawing which illustrates a carbureter in vertical 35 axial section.

In this drawing, the casing 1 provides the mixing chamber 2 which has the outlet 3 thereof controlled by the throttle 4 mounted upon the actuating shaft 5. The mixing 40 chamber is provided with two inlets, one in the form of a Venturi tube or carbureting chamber 6 and the other in the form of an opening 7 controlled by the valve 8, the former being the primary air inlet and the 45 latter being the secondary or auxiliary air inlet. Both air inlets lead from a primary air chamber 9 to which the outside air is admitted under the control of the choker valve 10.

50 The fuel nozzle 11 is disposed axially in the Venturi tube, this nozzle receiving liquid fuel, such as gasolene, from a constant level chamber 12 by way of a restricted passageway 13. Ordinary float

mechanism 14 is indicated as disposed within 55 the constant level chamber for the usual purposes.

What I have described thus far is old in the art. The precise form of the carbureting instrumentalities is not important. 60 My invention is applicable to either the so-called plain tube type of carbureter or the auxiliary air valve type of carbureter. It is immaterial whether the two air inlets of an auxiliary air valve carbureter, such 65 as shown in the drawing, receive the air independently from the outside or from a common air chamber such as the chamber 9. Incidentally, I have shown the auxiliary air valve 8 as carried with a piston 15 70 which, by way of the opening 16, is subject to the suction in the mixing chamber, the upper side of the piston being subject to atmospheric pressure, or substantially that, by way of the chamber 9 except when 75 the choker 10 is closed.

Coming now to the feature of my invention, it will be seen that the fuel nozzle 11 has its feeding outlet or outlets 17-17 in the side thereof, these outlets being disposed slightly above the most restricted 80 portion of the Venturi tube. A tube 18 extends downwardly from the throttle into and through the nozzle 11, as shown, this tube being open to the outside air at the 85 bottom, as indicated at 19. Within the nozzle 11 the tube 18 is provided with a small opening 20, this opening, like the openings 17-17 in the nozzle 11, being above the level of the liquid fuel in the 90 float chamber, indicated by the dot and dash line X-X. The annular space between the tube 18 and the nozzle 11 is such as to provide ample passageway for the liquid fuel and the tube itself closes the 95 top and bottom of the nozzle structure, as shown, although there may be an annular space between the top of the nozzle and the tube without harmful effect.

The top of the tube 18 is hung upon the 100 actuating shaft 5 upon which the throttle is mounted, it being understood that the shaft and the throttle may move relatively to the tube 18. The tube 18 passes through a suitable opening in the throttle 4, as illustrated, 105 and, above the throttle when the throttle is closed, an opening 21 is provided in the tube. I have constructed a carbureter of

this kind and secured the most desirable results by the use of a number seventy-four hole at 20 and a number sixty hole at 21. In view of this relationship and in view of the 5 fact that the bottom of the tube is open, there is assurance that the desirable feeding action, by way of the tube 18, takes place only upon idling and low speed. It is preferable that in the air valve type of carbureter there be such assurance so that the 10 proportions upon the higher speeds as determined by the other carbureting instrumentalities may not be upset or interfered with. The liquid fuel is drawn from the 15 interior of the main nozzle, as will be evident, to a point above the throttle, when the throttle is in closed or substantially closed position, the proportion of fuel to air under these circumstances being therefore very great and the fuel being fed into 20 a high instead of a low vacuum. The result is thorough volatilization, proper proportioning for low speed and idling, with the elimination of the possibility of the 25 deposit of liquid fuel on the walls of the Venturi tube and mixing chamber.

It will be obvious that at idle running or low speed air will pass inwardly through the main fuel orifices 17-17 and will mix 30 with the gasoline drawn up from the opening 13, the combined mixture being drawn into the tube 18 through the opening 20 when it will be mixed with further air drawn through opening 19.

35 It will be noted that the opening 21 is so arranged that after the throttle is opened slightly it begins to close and finally does close the opening so as to cut off the application of suction to the tube. As the throttle 40 is opened with a gradual increase in suction in the Venturi tube, a point is finally reached where the openings 17-17 begin to issue gasoline but at that time, it will be clear, the suction below the throttle is sufficient 45 to carry the gasoline upward into the engine.

I claim as new and desire to secure by Letters Patent:

1. In a carbureter, a carbureting chamber having an air inlet and a mixture outlet, a 50 throttle in said mixture outlet, a fuel nozzle feeding into said air inlet, and a tube open to the atmosphere at the bottom and extending through said nozzle and beyond said throttle, said tube being perforated above 55 the normal fuel level whereby it is fed from the interior of said nozzle.

2. In a carbureter, a carbureting chamber having an air inlet and a mixture outlet, a throttle in said mixture outlet, a fuel nozzle 60 feeding into said air inlet, and a tube extending through said nozzle and beyond said throttle, said tube being perforated above the nozzle outlet whereby it is fed from the 65 interior of said nozzle and being open to the atmosphere at the bottom.

3. In a carbureter, a carbureting chamber having an air inlet and a mixture outlet, a throttle in said mixture outlet, a fuel nozzle feeding into said air inlet, and a tube extending through said nozzle and beyond said 70 throttle, said tube being perforated whereby it is fed from the interior of said nozzle and having a feed outlet at the top open when the throttle is substantially closed and closed 70 by the opening movement of the throttle.

4. In a carbureter, a carbureting chamber having an air inlet and a mixture outlet, a throttle in said mixture outlet, a fuel nozzle feeding into said air inlet, and a tube extending through said nozzle and beyond said 80 throttle, said tube being perforated whereby it is fed from the interior of said nozzle and having a feed outlet at the top open when the throttle is substantially closed and closed 85 by the throttle upon its opening movement.

In witness whereof, I hereunto subscribe my name this 20th day of March, A. D. 1917.

FRANK C. MOCK.
